[57] CLAIM

The ornamental design for a combined closure and hook therefor, as shown and described.

DESCRIPTION

FIG. 1 is a perspective view of a combined closure and hook therefor showing my new design;

FIG. 2 is a front view thereof;

FIG. 3 is a right side view thereof, the left side view being a mirror image of the right side view;

FIG. 4 is a rear view thereof;

FIG. 5 is a top plan view thereof;

FIG. 6 is a bottom plan view thereof;

FIG. 7 is a perspective view of a second embodiment of the combined closure and hook, illustrated in FIG. 1;

FIG. 8 is a front view thereof;

FIG. 9 is a right side view thereof, the left side being a mirror image thereof;

FIG. 10 is a rear view thereof;

FIG. 11 is a top plan view thereof; and

FIG. 12 is a bottom plan view thereof.

FIG. 1

FIG. 5
